UNITED STATES PATENT OFFICE.

CHARLES Y. KNIGHT, OF PASADENA, CALIFORNIA, ASSIGNOR TO THE KNIGHT AMERICAN PATENTS COMPANY, OF CHICAGO, ILLINOIS, A CORPORATION OF DELAWARE.

INTERNAL-COMBUSTION ENGINE.

1,370,454.

Specification of Letters Patent.

Patented Mar. 1, 1921.

Application filed June 27, 1918, Serial No. 242,278. Renewed September 17, 1920. Serial No. 410,962.

To all whom it may concern:

Be it known that I, CHARLES Y. KNIGHT, a citizen of the United States, residing at Pasadena, in the county of Los Angeles, 5 State of California, have invented certain new and useful Improvements in Internal-Combustion Engines, of which the following is a specification.

This invention relates to that type of motor which comprises cylinders assembled around a crank shaft and which rotate about said crank shaft as an axis, and has for its object the provision of a motor of the character named which shall be of improved construction and operation. The invention is exemplified in the combination and arrangement of parts shown in the accompanying drawing and described in the following specification, and it is more particularly pointed out in the appended claims.

In the drawings—

Figure 1 is a side elevation of a motor embodying one form of the present invention; and

Fig. 2 is a vertical section on line 2—2 of Fig. 1.

In many of the uses to which internal combustion engines are put in modern practice, it has been found desirable to connect a plurality of cylinders so that they operate upon the same crank bearing, and this is especially true in air craft motors. Heretofore there have been two general types of motors which operate in this way, one in which the cylinders are stationary and disposed at different angles relative to the crank shaft as a center, and the other in which the crank shaft is stationary and the cylinders and associated parts are caused to rotate about the shaft. Motors of the first class are usually of the kind known as V-type motors, for the reason that it is not practical to distribute the cylinders so as to entirely surround the shaft, and it is therefore usual

to connect two cylinders to each crank bearing, arranged in the form of the arms of a V above the crank shaft. If more cylinders are connected with the crank bearing so that they extend downwardly from the shaft, it has been found that it is practically impossible to properly lubricate the downwardly projecting cylinders without interfering with their operation, for the reason that the lubricant naturally gravitates to the outer ends of the cylinders where it not only fouls the sparking apparatus, but also accumulates in suf-

ficient quantity to interfere with the operation of the piston.

In the other type of motor in which the cylinders are made to rotate about the shaft, 60 commonly called the Gnomme motor, difficulty has been experienced in properly lubricating the engine for the reason that the centrifugal force due to the rotation of the cylinders forces the lubricant to the outer 65 ends of the cylinders where it is discharged with the exhaust and so is lost after use but a single time. This makes it necessary to carry such a large quantity of lubricant as to limit the length of flight where an 70 engine of this character is employed. It is also practically impossible to water-cool an engine of this type, for the reason that the additional weight of the water-jacket and fluid within the jacket makes the rotating parts too heavy to permit of the high rate of rotation employed in the use of such engines.

In the present invention, the power is obtained from a rotating crank shaft, but the 80 engine frame and cylinders are also rotated at a comparatively low rate of speed so as to avoid the difficulties of lubricating cylinders extending downwardly in a fixed position relative to the crank shaft and yet 85 at the same time avoid also the difficulties arising from rotation of the engine cylinders at high speed such as has been previously employed in the Gnomme engines.

In the embodiment of the invention 90 shown in the drawing, the motor is illustrated as being mounted upon the forward end of an aeroplane frame, but it should be understood that the motor may be used with other apparatus as well as aeroplanes. The 95 numeral 10 designates the frame on which the motor is supported, and the numerals 11 and 12 designate bearings on opposite sides of the motor in which projecting trunnions 13 and 14 formed on the engine frame 100 itself are mounted for rotation. The engine frame 15 carries a plurality of radially arranged cylinders 16 which may be provided with water-jackets 17 if desired. The engine crank shaft 18 is journaled in 105 axially disposed openings in the trunnions 14 and is provided, in the usual manner within the engine casing 15, with a crank bearing to which the pistons in the cylinders 16 are connected in the well known 110 manner. Secured to a projecting end 19 of the crank shaft 18 is a pinion 20 which ro-

tates with the crank shaft and meshes with a gear 21 mounted on a stud shaft 22 which projects from the framework 10 as shown in the drawing. The gear 21 is provided 5 with a pinion 23 rigid therewith arranged to mesh with a second gear 24 mounted on a stud shaft 25 carried by the frame 10. The gear 24 has a sprocket pinion 26 rigid therewith and a sprocket chain 27 connects the sprocket wheel 26 with a larger 10 sprocket 28 formed on the rim of the motor casing or base 15. The mechanism described forms a chain of reduction gearing driven by the crank shaft of the engine and 15 arranged to rotate the engine base and cylinders at a comparatively low rate of speed during the operation of the engine. The rate at which the engine is rotated will vary somewhat, depending upon the size and 20 other characteristics of the particular motor, but it should be just fast enough to bring the lower cylinders from their inverted position and set up a churning effect before the lubricant has been given time to accumulate 25 at any point in sufficient quantity to foul the ignition points or to be wasted through the exhaust, or to interfere in any way with the operation of the moving parts, and should not be sufficiently rapid to produce 30 centrifugal force great enough to interfere with the lubrication of the parts or the circulation of the cooling medium. In the embodiment illustrated in the drawing, the total reduction of the gear train is approximately 35 1 to 100, but this ratio will be varied to suit various engine speeds and sizes.

Where an engine embodying the present 40 invention is water-cooled, the rotation of the engine parts effects a more complete cooling of all of the heated surfaces than can be readily attained where the cylinders are stationary, for the reason that the continual moving of the water-jackets prevents 45 the accumulation of pockets of steam and

consequent formation of hot spots. If steam begins to accumulate in any of the remote corners of the water-jackets, the change of position of the cylinders will soon force out the pocket of steam and reestablish the circulation of water in the place which it has occupied and so a better cooling of all of the parts of the engine is secured, due to the rotation of the frame and cylinders. 50

55 I claim:

1. In combination, a frame having fixed bearing portions spaced apart, a crankshaft journaled in said bearing portions and having its ends projecting therefrom, a member 6 to be driven on one end of said crankshaft, a gear mounted on the opposite end of the shaft outwardly from the nearest bearing portion, an engine casing carrying a plurality of cylinders mounted upon said crank 65 shaft between said bearing portions, a gear connected with said casing between said bearing portions, and driving connections between said gears whereby the crankshaft and casing are simultaneously rotated at 70 different rates of speed.

2. In combination, a frame having fixed bearing portions spaced apart, a crankshaft journaled in said bearing portions and having its ends projecting therethrough, a member 75 to be driven on one end of said shaft, a gear on the opposite end of the shaft, an engine casing carrying a plurality of cylinders mounted upon said crankshaft between said bearing portions, and a sprocket 80 upon the outer face of said casing between said bearing portions having a sprocket chain operatively connected with said gear whereby said shaft and said casing are rotated in opposite directions at relatively different speeds. 85

In testimony whereof I have signed my name to this specification on this 19th day of June A. D. 1918.

CHARLES Y. KNIGHT.
